UNITED STATES PATENT OFFICE.

ROBERT H. HASSSLER, OF INDIANAPOLIS, INDIANA.

MOTOR-VEHICLE.

SPECIFICATION forming part of Letters Patent No. 735,370, dated August 4, 1903.

Application filed January 15, 1901. Renewed January 13, 1903. Serial No. 138,829. (No model.)

To all whom it may concern:

Be it known that I, ROBERT H. HASSSLER, a citizen of the United States, residing at Indianapolis, in the county of Marion and State of Indiana, have invented certain new and useful Improvements in Motor Suspension for Electric Vehicles, of which the following is a specification.

This invention relates to the attachment of motor and driving wheels of an electric vehicle, whereby the shocks and jars due to the passage of the vehicle over rough places and also the shocks due to starting the motor or applying the brake will be absorbed by the springs and not transmitted to the body.

A further object of the invention is a compact and convenient arrangement of the parts.

In the accompanying drawings, Figure 1 is a side view of the vehicle with body and front wheel broken away. Fig. 2 is a view of the vehicle from the rear. Fig. 3 is a partial sectional view along the line *x y* of Fig. 1. Figs. 4 and 5 are sectional views, on an enlarged scale, of the shackles, Fig. 4 being taken along the line 4 4 of Fig. 5 and Fig. 5 being taken along the line 5 5 of Fig. 4.

Like letters of reference refer to like parts in the different figures.

The parts B B', consisting of dish-shaped castings, perform the combined functions of gear-case, motor-hanger, and axle-arch. To the part B are brazed three lengths of tubing *c*, *c*², and *c*³, which converge in and are brazed to the cluster-casting F. To the part B' are brazed three similar lengths of tubing, which converge in and are brazed to the cluster-casting F'. These cluster-castings carry spring-seats *q* *q*', to which are fastened the two rear elliptic springs K K' by means of the clips M M'. Through the tubes *c* *c*² pass the driving-shafts H H', rotating in bearings *h*, *h*², *h*³, and *h*⁴. (Not shown.) To the outer ends of these shafts are securely keyed and fastened the rear hubs G G', carrying the driving-wheels I I'. To the inner ends of the driving-shafts are keyed and fastened the bevel-gears P' P², which engage with the small bevel-pinions P³ P⁴.

S is the large driving-gear carrying the small bevel-pinions P³ P⁴ and journaled on the driving-shafts just outside the two bevel-gears. This arrangement of bevel-gears,

known as "differential," enables the driving-wheels to run at different speeds in turning corners and is well understood by those familiar with the art.

A is the motor with its armature-shaft T, with journals *e* *e*². To the shaft T are keyed the driving-pinion R inside the gear-case, engaging with the gear S and also the brake-drum *a* outside the gear-case. The braking action is effected by means of the band *b* *b*, which is tightened on the drum by means of the levers *j* *j*² *k*. The motor is securely bolted to the gear-case by means of cap-screws *d* *d*.

The upper portions of the elliptic springs K K' are attached by means of clips L L' to the spring-bars E E', which are securely bolted to the rear end of the body.

D is a cross-spring running transversely of the body. I prefer it with one or more leaves on its under side. Its middle portion is attached to the under side of the body by means of clips O O'. The ends of the cross-spring D are connected by means of shackles to the forward eyes of the rear elliptic springs, as shown at U U'. Each shackle consists of a piece W, drilled at right angles, bars or links U U', and the bolts that hold them together, all as shown in Figs. 4 and 5.

There is no perch or reach rod connecting the front and rear axles of the vehicle.

When the vehicle is running forward, the motor tends to rise and the ends of the cross-spring are pressed up. When the brake is applied, the motor tends to go down and the ends of the cross-spring and its lower leaf are pulled down by the action of the motor through the medium of the elliptic springs.

In order to limit the swing of the motor due to its torque and weight, it is usual in motors hung on the axle to connect the free end of the motor to a perch, frame, or by means of independent springs to the body. With my arrangement the swing of the motor is counteracted indirectly by the combined action of the cross-spring and the two elliptic springs that support the body. In this way all fastenings, springs, rubber cushions, or any other devices for directly limiting the swing and play of the motor are dispensed with altogether. This method gives great flexibility to all parts, and owing to the absence of any direct connection between the

body and the forward end of the motor the unpleasant vibration of the gear-wheels is not transmitted to the body. When the vehicle is driven over rough roads, both the body and the motor oscillate vertically, owing to their inertia and to the irregular torque of the motor. With this method of suspension these vertical oscillations of the motor and the body are independent of each other, and this independence conduces greatly to the easy-riding qualities of the vehicle.

The form of construction that I find to be best suited to the above-described method of motor suspension is that of a truss or system of tubes containing the driving-shaft journals and having its central portion forming the combined motor-hanger, gear-case, and axle-arch.

Inasmuch as the entire driving and braking system is connected with the body at only two points—namely, the parts q of the cluster-castings—it is necessary that great stiffness be secured between these cluster-castings and the motor. I obtain this stiffness by means of tubes, above described, that extend from the periphery of the gear-case to the cluster-castings. Inasmuch as the gear-case is fastened and braced with three tubes on each side I am enabled by holding the motor to the gear-case to distribute the strains due to the driving and braking torque of the motor-shaft uniformly over the truss and equally on each side.

While I prefer the form of truss here shown and described when minimum cost of produc-

tion is not a controlling element of manufacture, I am aware that rigid trusses may be made in various other forms at less cost, and I therefore do not desire to limit this invention to any certain construction of truss.

40

Having described the invention, I claim—

1. In a motor-vehicle, a body, a supporting-truss containing journals, driving-shafts running in the journals and actuating the vehicle-wheels and driven by means of a gear-wheel, 45 an electric motor secured to the truss, a pinion on the motor-shaft engaging with the gear, springs supporting the body on the truss, and a cross-spring having one portion attached to the body and other portions attached at the 50 ends of the first-mentioned springs.

2. In a motor-vehicle, a body, a supporting-truss containing journals, driving-shafts running in the journals and actuating the vehicle-wheels and driven by means of a gear-wheel, 55 a gear-case protecting the gear-wheel and forming a portion of the truss, an electric motor secured to the gear-case, a pinion on the motor-shaft engaging with the gear, springs supporting the body on the truss, and an auxiliary spring having one portion attached to the body and other portions attached to the 60 ends of the first-mentioned springs.

In witness whereof I have hereunto set my hand and seal, at Indianapolis, Indiana, this 65 10th day of January, A. D. 1901.

ROBERT H. HASSLER. [L. S.]
